UNITED STATES PATENT OFFICE

EDGAR P. HARRIS, OF TRIPPLETT, MISSOURI

ADJUSTABLE CAR PARTITION

Application filed October 21, 1928. Serial No. 401,262.

This invention relates to partitions or bulkheads for railway cars, and is especially adapted for use in stock cars.

An object of the present invention is to provide a partition which is designed for use in substitution of the ordinary temporary partition, the partition comprising the present invention being adjustably mounted and held in adjusted position so that it may be arranged at any point within the length of the car for use in dividing the car into separate compartments for stock of different character, or may be held out of the way when not in use. The invention therefore provides a partition which may be continuously used and arranged as desired, instead of the usual temporary partition which must be constructed for the occasion.

Another object of the invention is the provision of a partition, which in addition to the above and other advantages, is durable in construction, mounted for quick and easy adjustment, and conveniently and securely held in adjusted position.

With the above and other objects in view, the invention further includes the following novel features and details of construction, to be hereinafter more fully described, illustrated in the accompanying drawings and pointed out in the appended claim.

In the drawings:—

Figure 1 is a transverse sectional view of a stock car with the partition in position for use.

Figure 2 is an enlarged fragmentary section on the line 2—2 of Figure 1.

Figure 3 is a fragmentary perspective view illustrating the connection between the supporting axle or shaft and its wheels.

Referring to the drawings in detail wherein like characters of reference denote corresponding parts, the partition as shown is constructed of spaced walls 10. These walls are formed of horizontally arranged vertically spaced timbers which are secured to opposite sides of vertically disposed members 11, so that a rigid and compact partition or bulkhead is provided which may be arranged within a car 12 to divide the latter into separate compartments. This is especially de-

sirable in shipping cattle where cattle of different types and ages are shipped in the same car and provides means whereby the cattle may be separated for their protection.

The upper ends of the vertically disposed members 11 are swingingly mounted by means of straps 13 to a shaft or axle 14. This shaft or axle extends transversely of the car near the top and has secured upon opposite ends as shown at 15, wheels 16. These wheels 60 operate within tracks 17 which are secured to the inner walls or ceiling of the car and provide means whereby the partition may be readily moved the length of the car so that it may be positioned at any point throughout the car's length or may be positioned at one end of the car.

For the purpose of adjustably holding the partition in place the invention provides levers 18 which are pivotally mounted as 70 shown at 19 between the walls 10. These levers have their handles or grips 20 extending above the top of the partition so as to provide for ease of manipulation.

Pivotedly secured to the levers 18 upon opposite sides of the pivot 19 as shown at 20 are the inner ends of locking bolts 21. These bolts are horizontally arranged and are guided within openings provided in the standards 11 and their outer ends are adapted to be projected beyond or retracted within the opposite ends of the partition.

Arranged along the inner wall or ceiling of the car are keeper bars 22. These bars are preferably semi-circular in cross section 80 and are provided along their opposite edges with attaching flanges 23, whereby the bars may be secured in place. The bars are further provided with spaced openings 24 which may be arranged any desired distance apart to receive the ends of the bolts 21 and securely lock the partition in place. By arranging the levers 18 within the partition they are out of the way of the cattle so that the latter will not accidentally strike against and move these levers to release the partition.

The partition may be arranged upon either side of the car door to load the cattle and adjusted to the desired position. When not 100

in use the partition may be located against one of the end walls of the car.

Also, the partition may be elevated and held in elevated position. For this purpose the invention provides a hook 25 which is pivotally mounted as at 26 in a hanger 27 which depends from the roof structure of the car. A rope or cable 28 extends downwardly from one end of the hook.

10 The hook 25 is automatic in its operation and for this purpose is positioned within a slot 27' provided in the hanger 27. Normally, the bill of the hook rests against the lower edge of this slot due to the weight of this end of the hook. When the partition is raised, a loop or staple 29 carried at the lower end of the partition engages the hook at the juncture of the hook and hanger and forces the hook to swing upward. The loop or 15 staple passes the extremity of the bill of the hook and when the latter swings downward by gravity, the hooked end of the bill will pass through the loop or staple and hold the partition in the position shown by the dotted lines in Figure 2. In order to release the partition it is only necessary to slightly raise the end and pull the cable 28 to disengage the hook from the loop or staple.

20 30 The invention is susceptible of various changes in its form, proportions and minor details of construction and the right is herein reserved to make such changes as properly fall within the scope of the appended claim.

35 Having described the invention what is claimed is:—

30 40 In a car partition, elevated tracks adapted to be secured along the inside of a car, wheels movable along the tracks, a shaft connecting the wheels, a normally vertical partition swingingly supported by the shaft and adapted to be disposed transversely of the car, said partitions including spaced walls, levers pivotally mounted within the walls, 45 horizontally slideable bolts connected with the levers, and means adapted to be secured within the car for engagement by the levers to hold the partition against movement.

45 50 In testimony whereof I affix my signature.

EDGAR P. HARRIS.
